UNITED STATES PATENT OFFICE.

RAYMOND H. BANNING, OF SAN FRANCISCO, CALIFORNIA.

SCREEN ATTACHMENT FOR WINDOW-SASHES.

Specification of Letters Patent. Patented Aug. 18, 1914.

1,107,877.

Application filed March 9, 1912. Serial No. 682,743.

To all whom it may concern:

Be it known that I, RAYMOND H. BANNING, a citizen of the United States, residing in the city and county of San Francisco and State of California, have invented certain new and useful Improvements in Screen Attachments for Window-Sashes, of which the following is a specification.

The hereinafter described invention relates to the attachment of a screen to the upper slidable sash of windows in such a manner that the screen will extend and contract with the lowering and raising of the sash, whereby with the lowering of the said sash wholly or partially the opening which otherwise exists at the head thereof is screened to prevent insects entering the room; the roll carrying the screen having attached thereto the weight for the upper sash for giving a perfect balance thereto, whereby the window frame or casing may be constructed without having the usual pulleys fitted therein to receive the weight cords for the upper sash, inasmuch as the sash cords are transferred from the upper sash to reels or drums secured to the screen roll.

The objects of the invention are to simplify the attachment of screens to the upper sash of the window; to remove therefrom the direct connection thereto of the cords for the suspended sash weights; to provide for a perfect balance of the sash and screen attachment; to dispense with the employment of the pulleys in the window frame for the weights for the upper sash and by so doing saving in the cost of such pulleys and the expense incident to the proper placing of the same; to provide for the quick attachment and detachment of the screen relative to the upper sash of the window; and to provide a screen attachment fully protected and hidden from view, in fact, housed within the window casing, and of such a character as to be readily applied to the upper sashes of windows at present in use at a small expense.

With these objects in view the invention comprises the combination of the working elements or parts and the details of construction hereinafter fully described and pointed out, reference being had to the accompanying drawings for a comprehension thereof, wherein—

Figure 1 is a broken elevation disclosing the position of the screen mechanism relative to the window casing or frame, the con-

nexion between the free end of the screen and the upper sash of the window, and the manner of suspending the balance weights for the said sash and the screen attachment. 60 Fig. 2 is a perspective view of the angle-iron or attachment plate for uniting the screen to the top rail of the upper sash of the window. Fig. 3 is a detail view disclosing the ratchet and pawl for holding 65 the weight reels locked against movement when the screen is detached from the upper sash. Fig. 4 is a detail view of the supporting axles for the reels of the sash cords for the suspended weights. Fig. 5 is a view in 70 elevation of one of the end plates, disclosing the opening for receiving the end of the journal.

In the drawings, the numeral 1 is used to designate the upper sliding sash of an ordinary window, the same working within the usual frame or casing 2. To the top rail 3 of the sliding sash 1 is detachably united a transversely disposed angle-iron or attaching plate 4, to which is attached the lower 80 or free end of a screen 5. The angle-iron 4 is provided with a series of slots 6, through which extend the lock-catches 7, slidably held to the top rail 3 by means of the securing screws 8. When the lock-catches 7 are 85 turned to overlap the angle-iron 4, the same is held to the top-rail 3. The screen 5 extends from a roll 9 constructed of any suitable material, which roll is situated within a pocket 10 in the head 90 11 of the frame or casing 2, and the said roll is provided with the socket pieces 12 and 12' secured to the ends thereof. The screen roll 9 is held in place by means of the axles or journals 13 and 13', the reduced square 95 end 14 of the journal 13 and 14' of the journal 13' fitting within the respective socket-pieces 12 and 12', while the body portion of the said journals extends through bearings in the window jambs 15 and 15' and extend 100 respectively within the reels 16 and 16', to which they are united by tap screws 17.

The journal 13 is held inwardly pressed by means of the tension spring 17', which bears against the window jamb 15 and a collar 18^a on the said journal adjacent its reduced end 14, the tension or pressure of the spring 17' serving to hold the roll 9 in adjusted position relative to the journal 13'. The said journal 13, adjacent its reduced 110 end is formed or provided with a fixed ratchet wheel 18, which when it is desired to

hold the screen roll locked against rotation is engaged by a pawl 18' pivoted to the plate 19 secured to the inner face of the window jamb 15'.

- 5 To the reels 16 and 16' the sash cords 20 and 20' are attached in any suitable manner, to which cords are united the sash weights 21 and 21' suspended thereby within the weight pockets of the window frame or casing and the said weights are held in proper position by means of the guide rolls 22 over which the sash cords work, said rolls being carried by the brackets 22' secured within the weight pockets.
- 10 Access may be had to the overhead pocket 10 within which the screen roll 9 is situated by means of the removable bottom piece 23 of the casing or frame head 11, the said bottom piece 23 being slidably fitted in place.
- 15 In securing the roll 9 with the screen thereon in position within the pocket 10' the end carrying the socket piece 12 is first fitted onto the journal or axle 13 and forced endwise to depress the spring 17 and move inwardly the journal 13 to place the opposite end of the roll in alinement with the free end of the journal or axle 13' which is held against end movement by means of the ratchet 18 thereon, when the socket piece 12' is placed onto the squared end of the said journal or axle 13' by releasing the inward end pressure on the roll 9; the same being forced into place by the pressure of the spring 17'. The angle-iron or attachment 20 plate 4, to which the free end of the screen 5 is united is then secured to the top rail of the upper sash 1 by turning the lock catches or bolts 7 extended through the slotted portions 6 of the said angle-iron 4 or until the 25 said catches or bolts overlap the same.
- 25 With the parts assembled as above stated, as the upper sash of the window is lowered and raised the screen is unrolled from the roll 9 and wound thereon, due to the fact that as the sash is lowered the roll is rotated to unwind the screen, while on the sash being raised the suspended weights come into play and impart an opposite rotation to the said roll for the winding of the screen thereon, the weights lowering within the weight pockets and the unwinding of the weight cords from the reels 16 and 16' causing rotation of the roll 9 held to the journals or axles thereof. The expansion and contraction of 30 the screen 5 is thus proportioned to the

movement of the upper sliding sash, so no matter in what lowered position the sash stands, the space between the top rail thereof and the bottom of the casing head is always protected against the entrance of insects into the room by reason of the screen 5 covering said opening.

5 In case it is desired to remove the upper sash or disconnect the same from the screen for any purpose whatsoever, it is only required to lower the window sash and turn the lock catches or bolts 7 to stand in alinement with the slots 6 of the angle-iron or attaching strip 4, when the said strip may be lifted clear of the top rail of the sash. However, prior to releasing the angle-iron or strip 4, the pawl 18' pivoted to the fixed plate 19 is thrown into engagement with the ratchet wheel 18 to hold the roll 9 locked against rotation and thereby maintain the 75 weights in adjusted position.

80 I am aware that the detailed parts herein shown and described may be varied as to construction, and I do not wish to be understood as restricting the invention to such details of construction.

85 Having thus described the invention what I claim as new and desire to secure by Letters Patent is—

90 In an attachment for the described purpose, the combination with a screen roller, end sockets secured to the ends thereof and provided with squared receiving portions formed therein, journals provided on their inner ends with squared portions adapted to be inserted in said receiving portion for mounting the roller, one of said journals being held endwise under spring pressure and with the squared portion thereof seated within one of said squared receiving portions, and the other of said journals provided with a shoulder to prevent the longitudinal movement thereof, and the squared portion of said journal being received within the other of said squared receiving portions, 100 a reel for a sash weight cord detachably connected to the outer end of each journal, and a screen secured to the screen roller.

105 In testimony whereof I have signed my name to this specification in the presence of two subscribing witnesses.

RAYMOND H. BANNING.
